UNITED STATES PATENT OFFICE.

ARTHUR BOEMMEL, OF BALTIMORE, MARYLAND.

FIRE-ESCAPE.

SPECIFICATION forming part of Letters Patent No. 588,389, dated August 17, 1897.

Application filed May 11, 1896. Serial No. 591,094. (No model.)

To all whom it may concern:

Be it known that I, ARTHUR BOEMMEL, a citizen of the United States, residing at Baltimore, in the State of Maryland, have invented a new and useful Fire-Escape, of which the following is a specification.

My invention relates to fire-escapes, and has for its object to provide a simple, strong, and inexpensive device adapted to be folded or rolled to occupy a small space, whereby it may be placed in a room, under an article of furniture, or in any other convenient position to adapt it for use in an emergency, the same being provided with a plurality of spacing-frames of graduated lengths for holding the ladder in an inclined position with relation to the plane of the wall contiguous to which it is hung.

Further objects and advantages of this invention will appear in the following description, and the novel features thereof will be particularly pointed out in the appended claim.

In the drawing the figure represents a perspective view of a fire-escape constructed in accordance with my invention.

1 designates parallel cables, which may consist of wire or hemp rope, chain, or equivalent material, connected at intervals by the rounds 2.

Spacing-frames 3 of different sizes or having side bars or arms of graduated lengths are arranged at intervals upon the ladder to hold the cables in a position inclined to the plane of the wall contiguous to which the ladder is supported, whereby the hooks or grappling-irons 4 at the upper ends of the cables may be engaged with a window-sill or other object, while the ladder proper is held in such a position as to facilitate descent and prevent swinging. Said spacing-frames are preferably of rectangular construction with their front bars arranged contiguous to the planes of ladder-rounds and secured to the cables, while their rear bars are adapted to rest against the wall of the building, and the side bars or arms of the spacing-frames increase successively in length toward the bottom of the ladder.

To provide for the folding of the spacing-frames, they are loosely or pivotally connected to the terminals of the ladder-rounds, so that

the frames may be turned up or down to lie in the plane of the ladder cables and rounds. These foldable frames must be held in place when the ladder is unrolled and adjusted for service, and to accomplish this end I provide the holding ropes or cords 5, two of which are provided for each frame and which are arranged in a novel and peculiar way to be held taut by the tension of the ladder-cables and by the weight of the ladder. Each cord 5 is of a length proper to limit the unfolding movement of the spacing-frame, and said cords are loosely connected to the cross-bar 6 of the frame, and they have their terminals fastened to the ladder-rounds above and below the round to which the spacing-frame is pivoted. The cords being loosely connected to the spacing-frame, as by loosely coiling or wrapping the cords around the cross-bar of the frame, and the latter having its side bars loosely fitted on a ladder-round, the spacing-frame is adapted to turn on the round and to slide in the bight of the holding-cords when the ladder is unfolded, so that the strain of the ladder-cables on the holding-cords (which are attached to the rounds) operates to draw the holding-cords taut, and the holding-cords serve efficiently to hold the spacing-frame in its unfolded position. The spacing-frame is thus maintained in place in a plane substantially at right angles to the length of the ladder and in the horizontal plane of the round to which said frame is attached.

It will be understood that the strain or tension of the ladder cables and rounds serves to strain or pull the holding-cords which extend above and below the spacing-frame to which they are loosely attached, and thus the loops or bights of the holding-cords are drawn taut, and the cords hold the spacing-frames in place, the length of each cord being proportioned according to the distance the spacing-frame extends from the ladder, so that when the frame turns or unfolds outwardly the cords 5 will limit the movement of the frame, and as the cords themselves are drawn taut by the tension of the ladder cables or chains they hold said spacing-frame in place.

Beginning at the upper end of the ladder the spacing-frames increase in length successively from the top end of the ladder toward the bottom end thereof, and the holding-cords

are also increased in length proportionately to the increased size of the spacing-frames to which they are attached, in order to serve efficiently in holding said spacing-frames in 5 position.

As shown, the spacing-frames are of rectangular construction with side arms joined by an integral cross-piece. This construction enables the spacing-frame to be folded upon 10 or against the ladder and in the vertical plane of the cables or rounds thereof, so that the frames may fold compactly with the ladder.

When the ladder is unrolled or unfolded, the spacing-frames tilt or cant outward from 15 the ladder, and the weight of the ladder and the tension of the cables thereof draw on the cords 5 to maintain the spacing-frames in position approximately at right angles to the ladder. The spacing-frames being increased 20 in length successively from the top toward the bottom the ladder is held in an inclined position against the vertical wall of a building, so as to facilitate ascent and descent thereon.

Having described my invention, what I 25 claim is—

In a fire-escape ladder, the combination with flexible cables and the rounds connected thereto, of the series of spacing-frames which gradually increase in length from the top to 30 the bottom of the ladder and are each loosely attached to the terminals of one of the ladder-rounds, and a pair of holding-cords for each frame, said holding-cords being connected loosely to the outer cross-bar of the 35 spacing-frame and having their respective terminals fastened to the ladder-rounds above and below the round on which the spacing-frame is mounted, for the purpose described, substantially as set forth.

In testimony that I claim the foregoing as my own I have hereto affixed my signature in the presence of two witnesses.

ARTHUR BOEMMEL.
